DESIGN FOR A DIAL FOR WATCHES OR SIMILAR ARTICLES

Bernard Dupertuis, Rochelle Park, N. J.

Application October 18, 1940, Serial No. 95,922

Term of patent 7 years

To all whom it may concern:

Be it known that I, Bernard Dupertuis, a citizen of the United States and a resident of Rochelle Park, county of Bergen, and State of New Jersey, with a post-office address at No. 21 Sterling Place, Rochelle Park, county of Bergen, and State of New Jersey, have invented a new, original, and ornamental Design for a Dial for Watches or Similar Articles, of which the following is a specification, reference being had to the accompanying drawing, forming part thereof.

In which:

Figure 1 is a plan view of the dial for watches or similar articles, showing my new design.

Figure 2 is a fragmentary sectional view on line 2—2 of Figure 1.

Figure 3 is an enlarged perspective view of one of the facets or hour markings shown in Figure 1.

I claim:

The ornamental design for a dial for watches or similar articles, as shown.

BERNARD DUPERTUIS.
